UNITED STATES PATENT OFFICE.

DÉSIRÉ BAUDEWYNNS, OF MONTIGNIES-SUR-SAMBRE, BELGIUM.

FLAT HOISTING-CABLE.

1,070,661.

Specification of Letters Patent. Patented Aug. 19, 1913.

Application filed May 22, 1912. Serial No. 698,983.

To all whom it may concern:

Be it known that I, DÉSIRÉ BAUDEWYNNS, a subject of the King of Belgium, residing at Montignies-sur-Sambre, Belgium, have 5 invented new and useful Improvements in and Relating to Flat Hoisting-Cables; and I do hereby declare the following to be a full, clear, and exact description of the same.

10 The object of my present invention is to provide a flat hoisting cable by means of wires or textile materials or both and where- in two or more ropes each of which is formed of at least six strands or sections 15 are arranged side by side and connected together by means of one or more flat wires or threads, inserted through the ropes so that the two central strands of each rope are embraced by said connecting wires, 20 while the outer strands on opposite sides of the cable are not embraced by said wires. The purpose of this particular method of manufacturing cables is to produce cables of larger thickness and balance the load by 25 an adequate winding of the cable.

My invention is illustrated in the accom- panying drawings, wherein—

Figure 1 is a fragmentary front eleva- 30 tion of the cable; Fig. 2 is an edge view of same, and Fig. 3 is a cross-section of same.

My cable made of metal or textile mate- rial is composed of two or more ropes *a*, each of which is formed of at least six strands, *b*. Each rope is made with or with- 35 out inner core *a¹* of hemp or other textile material. Each strand of each rope is com- posed of more than two threads or wires *c* with or without core of hemp. The ropes of the cable are alternately twisted to the 40 right and the left and arranged side by side so as to obtain the desired width of the cable. The strands may be twisted in the same direction as the ropes or in opposite directions, even if metal and textile mate- 45 rials are used in mixture.

The ropes are connected together by means of one or more flat or semi-flat threads or wires, *d*, having rounded rims or edges and which are inserted through the 50 ropes so that the two central strands of each rope are embraced by the wires (Fig. 3) while the two outer strands on each face of the cable are outside the connecting wires.

As shown in the drawing the connecting wires may be wound several times around 55 the strands of each rope, so that a plurality of connecting wires may be superposed in the plane of the cross-section of the cable.

It is manifest that my cables may be manufactured of any number of wires, 60 strands and ropes of any type, diameter and material. The connection of the ropes may also be produced by means of any number of wires or threads of any suitable material. 65

The particular connection of the ropes as herein described insures the thickness of the cable remaining constant.

Having now particularly described the nature of my said invention and in what 70 manner the same is to be performed, I declare that what I claim and desire to secure by Letters Patent is:—

1. A flat metal or textile hoisting cable, composed of two or more ropes, each of 75 which is formed of at least six strands formed of more than two threads or wires, said ropes being arranged side by side and connected by means of one or more flat cords or wires with rounded edges, insert- 80 ed through the ropes so that the two central strands thereof are embraced by the cords or wires, while the remaining strands are outside the latter substantially as and for the purpose set forth. 85

2. A flat flexible cable comprising a plu- rality of twisted ropes, each composed of a plurality of twisted strands, bands uniting the central strands of all the ropes forming a flat cable, the exterior strands of said 90 ropes remaining free and forming the working surfaces of said cable.

3. A flat cable, comprising a plurality of ropes side by side, said ropes being com- 95 posed of a plurality of strands, and having the central strands of one rope mechani- cally united by separate and independent bands to those of another rope, forming a pliable cable.

In testimony whereof, I have signed my 100 name to this specification in the presence of two subscribing witnesses.

DÉSIRÉ BAUDEWYNNS.
